UNITED STATES PATENT OFFICE.

LEONARD R. STEEL, OF CHICAGO, ILLINOIS.

SHIPPING-CAN.

1,140,414.

Specification of Letters Patent. Patented May 25, 1915.

Application filed October 22, 1913. Serial No. 796,884.

To all whom it may concern:

Be it known that I, LEONARD R. STEEL, a citizen of the United States, residing at Chicago, in the county of Cook and State of Illinois, have invented new and useful Improvements in Shipping-Cans, of which the following is a specification.

This invention relates to shipping cans; and it has for its primary object the provision of a can of this character which will be constructed of separable portions that may be readily taken apart so that the inner portions of the can may be cleaned at the convenience of the user and maintained in a highly sanitary condition.

Another object of the invention is the provision of a structure of this character wherein one of the separable portions of the can will be constructed of asbestos or suitable insulating material and arranged as a receiver for the inner liquid holding vessel.

Another object of the invention is the provision of means for facilitating separation of the different sections or portions of the can or the connection of the sections together.

A further object of the invention is the provision of a basket for holding the inner vessel of the can, and further, the construction of the basket which will expedite the operation of removing the inner vessel from the outer vessel or the application of the inner vessel to the outer vessel.

With these and other objects in view, the invention consists of certain novel features of construction, combination and arrangement of parts, as will be hereinafter described and claimed.

In the accompanying drawings:—Figure 1 is a side view of the can; Fig. 2 is a vertical section; Fig. 3 is a perspective view of the cover for the outer vessel; Fig. 4 is a perspective view of the upper end of the outer vessel; and Fig. 5 is a perspective view of the basket.

The can comprises an outer vessel 1 provided with a body portion of cylindrical form having vertical walls 2. At the upper end the body section of the vessel is embraced by an annulus 3 secured at 4 by means of rivets 4', solder or the like to the vertical walls of the can and as shown said annulus is provided with a lateral continuous horizontal flange 5, from which threaded posts 6 rise. At the upper ends these posts

are provided with combined stop and guard heads 7 and adjustable on the posts beneath the heads are clamping nuts 8 for a purpose to be hereinafter referred to.

A packing and sealing gasket 9 is superimposed relatively of the flange 5 and is provided with passages 10 whereby the gasket may be properly placed over the vertical post 6. The outer vessel 1 is closed at its bottom by a cap 11 having a flange 12 embracing the lower vertical walls of the vessel and riveted thereto, as at 13. Embracing the flange of the cap 11 is an annulus 14, which is adapted to strengthen the lower portions of the vessel and to prevent the cap from directly resting upon the surface on which the can is mounted to also prevent the bottom of the vessel from being unduly indented while the can is in shipment.

A lining 15 of insulating material is removably mounted in the vessel 1 and as shown said lining consists of a lower section 16 and an upper closure section 17, the latter having a reduced lower portion 18 which fits in a receiving channel 19 formed in the inner walls of the lower section 16. This construction is desirable in order to increase the sealing action of the closure section and prevent the outside air from entering the lining.

Removably fitted within the lining is a basket 20 consisting of rings 21 and 22 connected by vertical bars 23 and a pair of vertical bars 24. These bars are preferably riveted, as at 25, to said rings. The bars 24 are disposed at diametrically opposite points and connected with each other at their lower ends by a cross bar 26, which is adapted to form a rest for the inner vessel 27. The side bars 24 are extended above the ring 21, as at 28 and provided with key-hole passages 29, said passages adapted to receive a hook to assist in the lifting action of the inner vessel from its lining. These extensions are adapted to fit in receiving passages 30 formed in the section 17 or cover member of the lining 15. This construction is desirable in order that the extensions will be disposed above the upper end of the lower section of the lining 15 when the cover 17 is removed. This facilitates the removal of the inner vessel from the outer vessel or the application of said vessel from the outer vessel. The vessel 27, which is

designed to contain the liquid to be stored or shipped consists of a lower section 31 and an upper closure section 32, the latter having a flange 33 which is adapted to embrace the reduced portion 34 at the upper end of the lower section.

The closure 35 of the outer vessel 1 comprises an annulus 36 closed at its upper end by a crown or disk 37 and at the lower end by the annulus is embraced by a collar 38 which is provided with a horizontal outwardly-extending flange 39 having a width co-extensive with the width of the flange 5 whereby the gasket of the latter may be properly introduced between said flange 5 and the flange 13 to effect a perfect airtight connection at this point. Said flange 39 is provided with an annular series of key-hole slots 40, which are adapted to receive the vertical posts 6 and to permit the closure section to be rotated on the flange 5 in order that the nuts 8 of the post may be disposed directly over the restricted branches 41 of the slots 40 and then adjusted against the flange 39 to secure the latter against the gasket. The closure 35 is bottomless, whereby the closure section 17 of the lining 15 may be projected thereinto when assembling the closure section 35 of the outer vessel 30 with the lower section of said vessel. This construction is also desirable in that the closure section 17 of the lining will be exposed above the open end of the outer vessel 1 when the closure of the latter is removed. In this manner the interior part of the can will be fully exposed to permit of their separation or the removal of the basket 20 from the lower section 16 of the lining. The construction described is such that the various parts may be separated and treated to a suitable sterilizing bath and maintained in a sanitary condition.

At diametrically opposite points upon the bottom 2 of the outer vessel 1 are mounted swinging handles 43, whereby the can may be conveniently carried from place to place. The crown of the closure section of the vessel 1 is also provided with a swinging handle 42, which is adapted to normally lie 50 in a horizontal position upon the can.

I claim:

1. A shipping can comprising an outer vessel, an inner vessel, a lining wholly embracing an inner vessel and removable therefrom and from the outer vessel and provided with a removable closure section, and a basket removably mounted in the lining.

and having extended portions fitting in the closure of said lining.

2. A shipping can comprising an outer vessel, an inner vessel, a closure for the outer vessel, a lining receiving the inner vessel and removably fitted in the outer section, a closure removably fitted to the lining and extending into the closure of the outer section, and a basket having extended portions lying above the upper end of the outer vessel and removably fitted in the cover of the lining.

3. A shipping can comprising an outer vessel having a removable closure, an inner vessel, a sectional lining receiving the inner vessel and removably fitted in the outer vessel, and a basket mounted in the lining and supporting the inner section therein and having portions extending above the outer vessel when the cover section of the latter is removed.

4. A shipping can comprising an outer vessel, an inner vessel, a lining wholly embracing the inner vessel and removable therefrom and from the outer vessel and provided with a removable closure section having a receiving passage; and means removably mounted in the lining and having diametrically opposed extended portions projecting above the upper edge of the outer vessel fitting in the receiving passage of the closure of said lining.

5. A shipping can comprising an outer vessel, an inner vessel, a lining wholly embracing the inner vessel and removable therefrom and from the outer vessel and provided with a removable closure section, and means removably mounted in the lining and having extended portions fitting in the closure of said lining, said extended portions having openings for permitting of the insertion of a lifting element.

6. A shipping can comprising an outer vessel, an inner vessel, a lining wholly embracing the inner vessel and removable therefrom and from the outer vessel and provided with a removable closure section, and a basket removably mounted in the lining and having diametrically opposed extended portions provided with openings fitting in the closure of said lining.

In testimony whereof I affix my signature in presence of two witnesses.

LEONARD R. STEEL.
